Primary Examiner — Ricky Pham

(57) **CLAIM**

We claim the ornamental design for a blender and enclosure, as shown and described.

DESCRIPTION

FIG. 1 is a front perspective view of the blender and enclosure of the present invention;

FIG. 2 is a rear perspective view of the blender and enclosure of FIG. 1;

FIG. 3 is a front elevation view of the blender and enclosure of FIG. 1;

FIG. 4 is a rear elevation view of the blender and enclosure of FIG. 1;

FIG. 5 is a first-side elevation view of the blender and enclosure FIG. 1;

FIG. 6 is a second-side elevation view of the blender and enclosure of FIG. 1;

FIG. 7 is a top plan view of the blender and enclosure of FIG. 1; and,

FIG. 8 is a bottom plan view of the blender and enclosure of FIG. 1.

The broken lines shown in the drawings are for illustrative purposes only and form no part of the claimed design.
